METHOD OF MAKING COMPLETE FUSE-STRIPS OF SAFETY-FUSES.

No. 862,938.

Specification of Letters Patent.

Patented Aug. 13, 1907.

Application filed June 15, 1906. Serial No. 321,808.

To all whom it may concern:

Be it known that I, FRANK D. REYNOLDS, a citizen of the United States, residing at Hartford, in the county of Hartford and State of Connecticut, have invented 5 an Improved Method of Making Complete Fuse-Strips of Safety-Fuses, of which the following is a specification.

My invention relates to safety fuses and to the smaller and more delicate safety fuses usually made 10 of round fuse wires and used where small current service is required and particularly to the method of making the complete fuse strip of such safety fuses. Heretofore in assembling the parts of the fuse strips of safety fuses of this class, the ends of the wire of 15 fusible metal have commonly been wound around the ends of terminal wires to connect these parts together, then the connections thus formed have been soldered or otherwise additionally connected both mechanically and electrically, whereupon the parts 20 have been placed within the casing of the fuse device and the terminal wires suitably connected to the terminal members of the two. Due to the smallness and consequent delicacy of the members forming the complete fuse strip of the fuses of this class and to the 25 tendency of these parts to break or rupture upon the slightest cause, great difficulty has been experienced both in making rigid connections between the fusible wire and the terminal wires, and in placing the same within the tube and making the necessary connections 30 between the terminal wires and the tube terminals, it being understood that the connections between the fuse wire and the wire terminals must be both good and rigid because otherwise the efficiency of the fuse device is immediately impaired.

Now the object of my present invention is to provide an improved method of connecting the fusible wire to the terminal wires wherein the connections between these parts may be made more rigidly than heretofore, and with much greater assurance of being 40 permanently rigid, thus saving time in the manufacture of the fuse device and also providing a more efficient article.

In carrying out the method of my present invention I first cut up the terminal wires into suitable lengths. 45 I then arrange to securely hold the said terminal wires at the ends to be joined to the fuse wire; then I wrap the ends of the fuse wire around the terminal wires; I then draw the terminal wires apart through the coils thus made at the ends of the fuse wire until 50 the ends of the terminal wires come up to the coils and I then solder the coiled ends of the fuse wire to the ends of the terminal wires whereupon the fuse strip is completed and ready to be placed within the fuse tube and connected to the terminals thereof.

I prefer to cut the ends of the terminal wires so as to

produce small burs thereon which act as stops when the terminal wires are drawn through the coiled ends of the fuse wire, and I prefer to employ a jaw clamping device of such a width as to agree approximately with the length of the fuse wire to be employed and which 60 clamping device serves to simultaneously engage and securely hold the adjacent ends of the terminal wires.

In the drawing, Figure 1 is a perspective view of the ends of the jaws of the clamping device holding the terminal wires in the position in which the ends of 65 the fuse wire are wrapped around the same, Fig. 2 is an end view of the jaws of the clamping device illustrating the parts in a similar position to that shown in Fig. 1.—Fig. 3 is an elevation of the terminal wires and the fuse wire and the relative positions in which 70 these parts are removed from the clamping device, Fig. 4 is a similar view of like parts showing the terminal wires withdrawn so that their burred ends contact with the coiled ends of the fuse wire, and Fig. 5 is a longitudinal section of the fuse strip inclosed 75 within the casing, all the figures being shown on a greatly enlarged scale.

In the drawing *a b* designate the terminal wires which may be made of any suitable conducting material. *c d* are the ends of the jaws of the clamping device; the width of the jaws of the clamping device being 80 exactly or approximately the length of the fuse strip *e* which is connected to the terminal wires *a b*, and *ff* designate end caps which are adapted to pass over and fit upon the respective ends of the suitable tubular 85 casing *g*.

In carrying out my improved method, the adjacent ends of the terminal wires *a b* are preferably first cut so as to provide small burs 2 thereon and these terminal wires are then placed within the jaws *c d* of the clamping device in such a position that the adjacent burred ends are in juxtaposition and the terminal wires *a b* in line with one another. The fuse wire *e* is then passed between or across the said jaws and the opposite ends thereof wrapped around that portion of the terminal 90 wires *a b* immediately protruding from the opposite side of the jaws *c d* as is indicated in Figs. 1 and 2, or I may first wrap one end of the fuse strip *e* around that portion of the terminal wire *a* immediately protruding from the jaws *c d* and then the other end of the strip *e* 100 around the other terminal *b* after first passing it between the jaws *c d*. I next remove the terminal wires *a b* and the fuse wire *e* connected as hereinbefore described from the jaws *c d* of the clamping device and draw the terminal wires *a b* apart or from one another 105 and through the coiled ends of the fuse wire *e* until (as illustrated in Fig. 4) the burred ends of the said terminal wires *a b* contact with and are arrested by the said coiled ends of the fuse wire, and I then solder the connections thus made between the burred ends of the ter- 110

minal wires to form a rigid mechanical and electrical joint between these parts. The complete fuse strip so made is then adapted to be placed within the tube *g* of the fuse device and the terminal wires *a b* connected to 5 ferrules or end caps *ff*.

By my improved method I am enabled to connect both terminal wires to the fuse strip and properly gage the length of said strip between the ends of the terminals with one handling operation.

10 I claim as my invention:

1. The method herein specified of making the complete fuse strip of safety fuses, consisting in first securely holding the terminal wires at the ends to be joined to the fuse wire, then wrapping around the terminal wires 15 the ends of the fuse wire and then soldering the wrapped ends of the fuse wire to the ends of the terminal wires.

2. The method herein specified of making the complete fuse strip of safety fuses, consisting in first simultaneously and securely holding the terminal wires at the ends 20 to be joined to the fuse wire, then wrapping around the terminal wires the ends of the fuse wire and then soldering the wrapped ends of the fuse wire to the ends of the terminal wires.

3. The method herein specified of making the complete 25 fuse strip of safety fuses, consisting in first securely holding the terminal wires at the ends to be joined by the fuse wire, then wrapping around the terminal wires the ends of the fuse wire, then drawing apart the terminal wires so that their ends come to the said wrapped ends, 30 then soldering the wrapped ends of the fuse wire to the ends of the terminal wires.

4. The method herein specified of making the complete 35 fuse strip of safety fuses, consisting in first simultaneously and securely holding the terminal wires at the ends to be joined to the fuse wire, then wrapping around the terminal wires the ends of the fuse-wire, then drawing apart the terminal wires so that their ends come to the said wrapped ends of the fuse wire to the ends of the terminal wires.

40 5. The method herein specified of making the complete fuse strip of safety fuses, consisting in first cutting the ends of the terminal wires to produce burs, then securely holding said terminal wires at the ends to be joined by the fuse wire, then wrapping around the terminal wires 45 the ends of the fuse wire and then soldering the wrapped ends of the fuse wire to the ends of the terminal wires.

6. The method herein specified of making the complete 50 fuse strip of safety fuses, consisting in first cutting the ends of the terminal wires to produce burs, then securely holding said terminal wires at the ends to be joined to the fuse wire, then wrapping around the terminal wires the ends of the fuse wire, then drawing apart the terminal wires until their burred ends come in contact with the said wrapped ends and are arrested thereby, then 55 soldering the wrapped ends of the fuse wire to the ends of the terminal wires.

7. The method herein specified of making the complete 60 fuse strip of safety fuses, consisting in first cutting the ends of the terminal wires to produce burs, then simultaneously and securely holding the said terminal wires at the adjacent ends to be joined to the fuse wire, then wrapping around the terminal wires the ends of the fuse wire, then drawing apart the terminal wires until their burred ends come in contact with the said wrapped ends and are arrested thereby, then 65 soldering the wrapped ends of the fuse wire to the ends of the terminal wires.

burred ends come in contact with and are arrested by the said wrapped ends and then soldering the wrapped ends 65 of the fuse wire to the ends of the terminal wires.

8. The method herein specified of making the complete fuse strip of safety fuses, consisting in taking a jaw clamping device of a width agreeing with the desired length of the fuse wire, then simultaneously and securely holding the terminal wires at the adjacent ends to be joined to the fuse wire, then wrapping around the terminal wires the ends of the fuse wire, then drawing the terminal wires apart and then soldering the wrapped ends of the fuse wire to the ends of the terminal wires. 70

9. The method herein specified of making the complete fuse strip of safety fuses, consisting in taking a jaw clamping device of a width agreeing with the desired length of the fuse wire, then cutting the ends of the terminal wires to produce burs, then securely holding said 80 terminal wires by said clamping device at the adjacent ends to be joined to the fuse wire, then wrapping around the terminal wires the ends of the fuse wire, then drawing apart the terminal wires until their burred ends come in contact with and are arrested by the said wrapped ends, 85 then soldering the wrapped ends of the fuse wire to the ends of the terminal wires.

10. The method herein specified of making the complete fuse strip of safety fuses, consisting in taking a jaw clamping device of a width agreeing with the desired 90 length of the fuse wire, then simultaneously and securely holding the terminal wires, then wrapping the ends of the fuse wire around the said terminal wires, then drawing the said terminal wires apart and then soldering the wrapped ends of the fuse wire to the terminal wires.

11. The method herein specified of making the complete fuse strip of safety fuses, consisting first in taking a jaw clamping device of a width agreeing with the desired length of the fuse wire, then cutting the end of the terminal wires to produce burs thereon, then securely holding 100 said terminal wires by the said clamping device, then wrapping the ends of the fuse-wire around the terminal wires, then drawing apart the terminal wires until their burred ends come in contact with and are arrested by the said wrapped ends of the fuse wire, and then soldering the wrapped ends of the fuse wire to the terminal wires. 105

12. The method herein specified of making the complete fuse strip of safety fuses consisting in first simultaneously securely holding the terminal wires at the ends to be joined to the fuse wire and gaging the length of the fuse wire, then wrapping around the terminal wires the ends of the fuse wire, then drawing the terminal wires apart and then soldering the wrapped ends of the fuse wire to the ends of the terminal wires. 110

13. The method herein specified of making the complete fuse strip of safety fuses consisting in first simultaneously securely holding the terminal wires at the ends to be joined to the fuse wire and gaging the length of the fuse wire, then wrapping around the terminal wires the ends of the fuse wire, and then soldering the wrapped ends of the fuse wire to the ends of the terminal wires. 115 120

Signed by me this 31st day of May 1906.

FRANK D. REYNOLDS.
